CAN WASHER

William de Back, Niagara Falls, N. Y., assignor to
 Chisholm - Ryder Company, Incorporated,
 Niagara Falls, N. Y., a corporation of New York

Application January 6, 1941, Serial No. 373,275

19 Claims.

(Cl. 141—7)

This invention relates to a can washer and more particularly to a machine for continuously washing and sterilizing the procession of cans being conveyed to apparatus for filling the cans with foodstuffs.

One of the principal objects of the invention is to provide such a can washer and sterilizer which is adapted to be inserted in an inclined canway along which the empty cans are conveyed by gravity thereby to provide for the washing and sterilization of the cans without altering or disturbing the arrangement of the existing system through which the cans are passed.

Another object of the invention is to provide such a can washer and sterilizer which is in the form of a self-contained unit capable of being suspended from or supported by any suitable support and which can be readily incorporated in any canway.

Another object of the invention is to provide such a can washer and sterilizer in which the cans are thoroughly washed and sterilized while passing in a continuous procession and in which the cans are thoroughly drained before being discharged.

Another object of the invention is to provide such a can washer and sterilizer which is readily accessible for the purpose of cleaning and adjustment.

Another object is to provide such a can washer and sterilizer in which the cans are positively propelled without danger of injury to the empty cans.

Another purpose is to provide such a can washer in which out of round cans are restored to their proper cylindrical form.

Another purpose is to provide such a can washer and sterilizer which is readily adjusted to handle different sized cans.

Another purpose is to provide such a can washer and sterilizer which is automatically started in operation by the cans first rolling down the canway into the can washer and sterilizer and in which the operation of the can washer and sterilizer continues as long as the line of cans progresses through the machine.

Another purpose is to provide such a can washer and sterilizer the operation of which is automatically stopped after all of the line of cans has passed through the same.

Another aim is to provide such a can washer and sterilizer which is also automatically stopped in the event that the movement of the line of cans leaving the can washer and sterilizer is obstructed.

Other objects are to provide such a can washer which is extremely compact and simple in construction and which will function efficiently and stand up under conditions of severe and constant use without getting out of order or requiring repairs.

In the accompanying drawings:

Fig. 1 is a rear elevation of a can washer and sterilizer embodying my invention and showing the manner in which it is inserted into an inclined canway.

Fig. 2 is a side elevation thereof viewed from the inlet side.

Fig. 3 is a front elevation.

Fig. 4 is a vertical section taken on line 4—4, Fig. 2.

Fig. 5 is a wiring diagram showing the manner in which the electrical connection is made between the control switches, the solenoid valve, and the drive motor.

Fig. 6 is an enlarged fragmentary vertical section taken on line 6—6, Fig. 4.

Fig. 7 is an enlarged fragmentary section taken on line 7—7, Fig. 4.

Fig. 8 is a greatly enlarged section similar to Fig. 6 and showing, in greater detail, the construction of the nozzles which discharge steam and hot water into the interiors of the passing line of cans.

Fig. 9 is a horizontal section through the solenoid valve controlling the admission of steam and hot water to the hopper, this section being taken on line 9—9, Fig. 6.

Fig. 10 is a vertical section, taken on line 10—10, Fig. 6.

Figs. 11 and 12 are vertical sections, taken on the correspondingly numbered lines of Fig. 10.

The can washer and sterilizer forming the subject of the present invention is adapted to be inserted in an inclined canway 20, indicated by dotted lines in Fig. 1, the empty cans 21 rolling down this canway being carried in a circular looped path through the sterilizer and washer and being returned to the downstream part of the canway 20 for delivery to the can filling machine.

While traversing the circular looped path through the can washer and sterilizer, the cans are rotated and sprays of hot water and steam are directed into the cans to thoroughly

clean and sterilize them and the cans are held in an inclined position so that the wash water immediately drains out. The cans are positively carried through the washer and sterilizer in a manner which tends to true up any cans which are out of round and the washer and sterilizer

is rendered entirely automatic in its operation, starting when the line of cans first enters, stopping when the trailing end of the line of cans leaves and stopping whenever the movement of the cans in the downstream part of the canway is impeded, as by shutting down the can filling machine.

The housing for the can washer and cleaner is shown as comprising a casting having a cylindrical lower part 25 which is open at its front 10 and having a peripheral wall 26 and a flat rear wall 27. At the upstream side of the housing, the flat rear wall 27 is extended upwardly, as indicated at 28 to provide the rear wall of an inlet neck 29 and at the downstream side of the housing the flat rear wall 27 is extended upwardly and laterally, as indicated at 30, to provide the rear wall of an outlet neck 31. A central generally vertical forwardly extending partition 32 forms the separating wall between the inlet and outlet necks 29 and 31, this partition dividing at 15 its upper end to provide the curved top wall 33 for the inlet neck 29 and a curved top wall 34 for the outlet neck 31. The cans delivered by gravity into the inlet neck 29 from the upstream part of the canway 20 are supported by a forwardly projecting ribbed shelf or bottom wall 35 which delivers the rolling cans against the central partition 32. This partition deflects the cans into a circular passage 36 in the cylindrical housing through which the cans are positively propelled in a counterclockwise direction as viewed in Fig. 10, as hereafter described. From the circular passage 36, the cans are delivered into the outlet neck 31 in which the cans are supported on a ribbed bottom wall 37 of this outlet neck. As best shown in Fig. 10, this bottom wall 37 of the outlet neck is provided with an inner elevated portion 39 forming a shoulder 40 over which the cans are delivered to a depressed outer portion 41. From the outlet neck the cans 21 are delivered to the downstream part of the canway 20. The inlet and outlet necks 29 and 31 are in line with each other so that the housing can readily be inserted in a straight section of the canway 20.

The rear walls 28 and 30 of the inlet and outlet necks 29 and 31 are arranged in a vertical plane and the top walls 33 and 34 and the bottom walls 35 and 37 of these necks extend horizontally forward therefrom so that the inlet and outlet necks align properly with the upstream and downstream parts of the canway 20. However, the axis of the lower cylindrical part 25 of the housing is inclined relative to the horizontal so that its rear wall 27 is inclined relative to the vertical plane of the rear walls 28 and 30 of the inlet and outlet necks 29 and 31, as best shown in Figs. 2 and 6. The lower cylindrical part 25 of the housing is inclined in this manner so that the cans 21 are carried around the circular passage 36 in a tipped or inclined position to drain the wash water which is sprayed into the interior of the line of cans. This wash water is discharged through a drain 42 in the bottom of the housing 25.

To guide the cans in their passage through the inlet neck 29, circular passage 36 and outlet neck 31, the rear walls 28, 27 and 30 are formed to provide a pair of spaced forwardly projecting shallow ribs 43 which follow the path of the cans through the washer and against which the rims at the open ends of the cans are adapted to bear and in the outlet neck 31, a third rib 44 is shown as interposed between the pair of ribs 43.

The open front of the cylindrical lower portion 25 of the housing is closed by a removable cover plate 45 which can be removably secured in any suitable manner as by wing nuts 46 applied to the ends of tie rods 47. The open fronts of the inlet and outlet necks 29 and 31 and the top part of the cylindrical housing 25 are covered by a plate 48 which can be removably secured in any suitable manner as by screws 49.

A gasket 50 can be interposed between the lower part cover plate 45 and the peripheral wall 26 of the casting 25 to prevent the leakage of wash water, and to the inner faces of the front cover plates 45 and 48 are preferably welded shallow ribs 51 and 52 which conform to the shallow ribs 43 and 44 cast in the rear walls of the housing and which serve to engage the bottom rims of the passing cans 21 and guide them through the washer.

At its center the upper front cover plate 48 is extended laterally over the housing 25 to provide a bed 55 for an electric motor 56, this bed being suitably braced as indicated at 51. To the front end of the shaft of this motor is secured a drive pulley 58 which is connected by a belt 59 with a pulley 60 on the front end of a horizontal drive shaft 61. As best shown in Fig. 6, this drive shaft is journaled in a pair of bearings 62 provided on top of the partition 32 intermediate the top walls 33 and 34 of the inlet and outlet necks 29 and 31 and extends through an opening 63 provided on the upper front cover plate 48. A pinion 65 is fast to the rear end of the drive shaft 61 and meshes with a large gear wheel 66 fast to a shaft 67 which is journaled in an elongated bearing 68 provided in the rear wall 27 of the housing and projects into this housing, as best shown in Fig. 6. This bearing 68 and its shaft 67 are coaxial with the cylindrical lower part of the housing 25 and hence this shaft 67 is inclined to the horizontal.

A wheel 70 having a broad rim 71 is fast to the forward end of the shaft 67 and is arranged coaxially within the lower cylindrical part 25 of the housing, this rim carrying a facing or tire 72 of a soft, resilient material such as rubber. This rubber facing 72 of the wheel 70 forms the means for positively propelling the empty cans through the can washer.

For this purpose, as best shown in Figs. 6 and 10, an annular series of shoes or plates 75 are arranged within the cylindrical lower part of the housing 25 and are mounted to yieldingly hold the cans 21 against the rubber facing of the wheel 70 in their movement through the circular passage 36. Each of these shoes or plates 75, as best shown in Fig. 10, has its leading edge bent outwardly, as indicated at 76, and its trailing edge also bent outwardly, as indicated at 77, to insure the smooth transfer of the cans from one shoe to the next and the shoes are comparatively narrow in a fore and aft direction so as to engage the cans at their centers, as shown in Fig. 6.

Each of these shoes 75 is formed to provide a pair of outwardly extending ears 80 which carry a pivot pin 81, these pivot pins 81 extending tangentially of the circular passage 36. To each of these pins is secured the forwardly extending arm 85 of a bell crank lever 86 the other arm 87 of which extends radially inward toward the shaft 67. Each of these bell crank levers 86 is pivotally supported on a pin 88 which is in turn supported by a pair of ears 89 projecting rearwardly from the rear wall 27 of the housing 25 and integral therewith. Each of these pins 88 is arranged

parallel with the corresponding pivot pin 81 and the arm 85 of each bell crank lever projects forwardly through an opening 90 provided in the rear wall 27 of the housing 25 between the corresponding pair of supporting ears 89. The swinging movement of each of the shoes 75 about its pivot pin 81 is limited by engagement with its supporting arms 85 on opposite sides of the pivot pin 81, each of these arms being extended beyond its pivot pin 81, as indicated at 91, for this purpose.

To hold the round walls of the line of cans 21 yieldingly in engagement with the rubber facing 72 of the drive wheel 70, a helical compression spring 95 is interposed between the rear wall 27 of the housing 25 and each of the radial arms 87 of the bell crank levers 86. For this purpose each of these radial arms 87 of the bell crank levers 86 is provided adjacent the supporting pin 88 with a forwardly opening cup shaped socket 96 which houses the rear end of the corresponding helical compression spring 95. The front end of each of these springs 95 embraces a retaining pin 97 formed integrally with the rear wall 27 of the housing 25 and projecting rearwardly therefrom adjacent the corresponding opening 90.

The degree or range of movement of the bell crank lever 86 is limited by an oversize peripheral channel 100 provided in an axially movable sleeve 101 loosely mounted on the rearwardly projecting end of the elongated bearing 68, as best shown in Figs. 4, 6 and 7. For this purpose the free end of each of the arms 87 of the bell crank levers 86 is provided with a rounding head 102 which is disposed within the peripheral channel 100, as best shown in Fig. 6, but is substantially smaller than this channel so that the bell crank lever is free to move within the limits provided by this channel, in response to variations in the diameters of the cans 21 and in response to the yielding returning movement of the helical compression springs 95. Thus if any of the cans 21 are out of round, the shoes 75 are permitted to yield to accommodate the enlarged diameter of these cans in the direction of the bulge, until the cans are restored to their round form on being rolled along between the succession of shoes 75 and the rim of the driving wheel 70.

The can washer is capable of being adjusted to handle cans of different sizes and for this purpose means are provided for adjusting the position of the sleeve 101 which controls the normal distancing of the annular series of shoes 75 from the rubber surface of the drive wheel 70. For this purpose a shifting fork 105, as best shown in Figs. 4 and 7, is provided, this shifting fork having an aperture 106 at its center which receives an ear 107 carried by the rear wall 27 of the housing 25 and being connected to this ear by a pivot pin 108. The inner end of the fork 105 is bifurcated to provide a pair of arms 109 which embrace the sleeve 101 and each of these arms is provided with an inwardly extending pin 110 which is arranged within the channel 100 of the axially movable sleeve 101. The outer end of the fork 105 is formed to provide a handle 111 which traverses a scale plate 112 which is suitably secured to the rear wall of the outlet neck 31, this scale being preferably graduated in accordance with the different sized cans handled by the washer. For the purpose of adjusting the handle 111 of the fork 105 to different positions along the scale 112, a curved threaded rod 115 is anchored in an ear provided at the corner between

the rear and peripheral walls 27 and 26 of the housing 25, as best shown in Fig. 7, and projecting rearwardly through an aperture provided in the handle 111 of the fork 105. Nuts 116 are provided on this curved threaded rod 115 on opposite sides of the handle 111, the adjustment of these nuts, of course, determining the position of the handle along the scale 112 and hence the position of the sliding sleeve 101 and the normal position of the annular series of shoes 75 which are positioned by this sleeve.

While traversing the circular passage 36 in the housing 25, the interior of the empty cans 21 are sprayed first with hot water and then with steam as they roll around between the central drive wheel 70 and the annular series of yielding shoes 75. For this purpose, the rear wall 27 of the housing 25 is formed on its rear side to provide a loop-shaped manifold 120, one end of which is formed to provide a boss 121 which is connected with a hot water pipe 122 and the other end of which is formed to provide a boss 123 which is connected with a steam pipe 124. These bosses 121 and 123 are shown as located near the top of the housing and to divide the manifold 120 into hot water and steam sections a partition 125 of any suitable form, as shown in Fig. 4, can be provided in the manifold. The hot water pipe 122 admits hot water to that side of the manifold 120 adjacent the inlet neck 29 and the steam pipe 124 admits steam to that side of the manifold adjacent the outlet neck 31.

To discharge the hot water and steam so admitted to the manifold 120 axially into the interior of the empty cans 21 traversing the circular passage 36, an annular series of nozzles 130 is provided in the rear wall 27 of the housing 25 and communicate with the interior of the manifold 120. Each of these nozzles 130, as best shown in Fig. 8, comprises a threaded stem 131 which is screwed into an opening 132 provided in that part of the rear wall 27 of the housing which forms the front wall of the manifold 120, and an enlarged head 133 which is formed to provide a wrench socket 134. Each nozzle is provided with an axial bore 135 leading to a discharge orifice.

The nozzles 130 are screwed into the rear wall 27 of the housing from the rear side thereof and for the purpose of applying a wrench to the socket 134 of each of the nozzles and of completely removing each nozzle from the manifold, the manifold 120 is provided in its rear wall and in register with each nozzle with a removable screw plug 136 of sufficient size to permit the withdrawal of the nozzles.

Since the cans pass with their open ends facing the wall 27, it will be seen that the interior of the cans are thoroughly sprayed, first with hot water and then with steam so as to be thoroughly washed and sterilized. Since the axis of the lower cylindrical part of the housing 25 is disposed at a slight angle to the horizontal in which the wash water will drain out of the cans, it will be seen that the cans are thoroughly drained as well as washed.

The admission of both the steam and the hot water to the manifold 120 is under the control of a valve 140 actuated by a solenoid 141. As best shown in Fig. 9, this solenoid actuated valve includes a cylindrical body 142 having an axial through bore 143 in which a valve rod 144 is fitted, one end of the through bore being closed by a screw plug 145 and the other end being closed by a stuffing box 146 which surrounds the

valve rod 144. The valve body 142 is provided at one side with a pair of bosses 147 and 148, the boss 147 having a bore 149 communicating with the through bore 143 and connecting with the steam pipe 124 and the boss 148 having a bore 150 communicating with the through bore 143 and connecting with the hot water pipe 122. On the opposite side of the valve body, a pair of bosses 155 and 156 is provided, the boss 155 having a bore 157 communicating with the through bore 143 opposite the bore 149, and connecting with a steam supply pipe 158 and the boss 156 having a bore 159 communicating with the through bore 143 opposite the bore 157 and connecting with a hot water supply pipe 160.

The solenoid 141 can be of any suitable form and is shown as contained within an enclosing body 161 supported on an extension 162 of the valve body 142. When the solenoid 141 is energized its core (not shown) is actuated to move the valve rod 144 to the left, as viewed in Fig. 9, or away from the screw plug 145. In this position of the valve rod 144 a reduced portion 165 of the valve rod is brought into register with the steam bores 149 and 157 and a reduced portion 166 of the valve rod is brought into register with the hot water bores 150 and 159 so that both steam and hot water can flow from the supply pipes into the pipes connecting the valve with the manifold, the hot water flowing from the hot water supply pipe 160 through the bore 159 past the reduced part 166 of the valve rod 144 and through the bore 150 and pipe 122 into the right hand side of the manifold 120, as viewed in Fig. 4, from which it is discharged through the nozzles 130 into the cans traversing the left half of the circular passage 36, as viewed in Fig. 10.

Similarly the steam from the steam supply pipe 158 flows through the bore 157, past the reduced part 165 of the valve rod 144 and through the bore 149 and pipe 124 into the left hand side of the manifold 120, as viewed in Fig. 4, from which it is discharged into the cans traversing the right half of the circular passage 36, as viewed in Fig. 10.

When the solenoid 141 is deenergized, a helical compression spring 170 acting against a collar 171 fast to the valve rod 144 moves the valve rod to the extreme right position illustrated in Fig. 9 in which enlarged parts of the valve rod 144 block the flow of hot water from the bore 157 to the bore 149 and block the flow of steam from the bore 159 to the bore 150 thereby to cut off the flow of both the steam and hot water to the can washer.

As shown in the wiring diagram, Fig. 5, the electric motor 56 and the solenoid 141 are connected by lines 175 and 176 and the line 176 connects with a main power line 178. The other main power line 179 is connected, in series, through a normally closed discharge switch 180 and through a wire 177 and a normally open feed switch 181 with the other line 175 between the electric motor 56 and the solenoid 141. These switches are shown as being of the mercury tube type each having a glass tube containing a globule of mercury which closes a circuit through the switch when it is tilted so the mercury flows from the bulb of the tube into engagement with the contacts at the base of the tube. The feed switch 181, as best shown in Figs. 4, 10 and 11, is mounted on a collar 185 fast to a rock shaft 186 journaled on the top wall 33 of the inlet neck 29 and extending transversely of the movement

of the line of cans therethrough. A curved lever 187, as best shown in Fig. 10, is fast to this rock shaft 186 and projects through an opening 188 in this top wall. The curved lever 187 generally conforms to the curvature of the partition 32 and is held against the partition by the line of moving cans passing through the washer. In this position of the lever 187 the normally open feed switch 181 is tilted to a position in which the globule of mercury establishes a circuit therethrough. When the trailing end of the line of cans passes beyond the curved lever 187, it swings to a pendant position in which the rock shaft 186 is rocked in a counterclockwise direction, as viewed in Fig. 4, to move the feed switch to its open position, as illustrated in Fig. 5.

The discharge switch 180 is mounted on a collar 190 fast to a rock shaft 191 journaled on a vertical supporting plate 192, as best shown in Figs. 4, 10 and 12. To adjust the switch, the supporting plate 192 is adjustably mounted on the rear vertical wall 30 of the outlet neck 31 and for this purpose, the supporting plate 192 is provided with a pair of diagonally upward extending slots 193 through which studs 194 carried by the rear wall 30 of the outlet neck 31 extend. After proper adjustment of the position of the supporting plate 192, nuts 195 on the studs 194 are tightened against the supporting plate 192 to hold it in position.

A rock arm 196 is fast to the rock shaft 191 and inclines downwardly and in the direction of the line of movement of the cans through the outlet neck 31 through an opening 197 provided in the top wall 34 of this outlet neck. At the opposite end of the supporting plate 192, a similar rock shaft 198 and rock arm 199 are journaled on the supporting plate, the rock arm 199 extending through the opening 197 in the top wall 34 of the outlet neck parallel with the rock arm 196. Pivoted to the lower ends of these rock arms 196 and 199 is the central upstanding web 200 of a shoe 201. The advance end 202 of this shoe inclines sharply upward and preferably extends upwardly through the opening 197 in the top wall 34 of the outlet neck 31 so as to insure the free movement of the line of cans under this shoe. Immediately above the shoulder 40 in the bottom wall 37 of the outlet neck, the bottom of the shoe 201 is formed to provide a curved recessed portion 203 which slopes downwardly in the direction of movement of the cans through the outlet neck, as best shown in Fig. 10. The trailing part 204 of the shoe is horizontally disposed.

As long as the line of cans is progressing through the outlet neck 31, as illustrated by full lines in Fig. 10, the shoe 201 is out of contact with the cans and hangs in the pendant position illustrated by full lines in this figure. In the event, however, of an obstruction to the movement of the line of cans leaving the outlet neck 31, as when the cans are fed to a can filling machine which is intermittently operated or stopped for any purpose, the positive feeding of the cans by the rubber faced wheel 70 causes the cans in the outlet neck 31 to pile up. Since the can which has just passed over the shoulder 40 in the outlet neck 31 is at a lower elevation than its succeeding can which lies on top of the elevated portion 39 of the bottom wall 37 of the outlet neck, this forced piling up of the cans in the outlet neck causes this last can to ride up on the preceding can which has just passed over the shoulder 40. This upward movement of this

last can causes it to engage the shoe 201, as indicated by dotted lines in Fig. 10, and to raise this shoe. This upward movement of the shoe 201 causes the rock shaft 191 to swing the discharge mercury tube type switch 180 in a clockwise direction, as viewed in Fig. 4, to its open condition.

In order to enclose the gears at the rear of the can washer and also the radially extending arms 87 of the bell crank levers 86 and to prevent the escape of wash water from the can washer, these parts are enclosed by a sheet metal casing having a peripheral wall 210 and a rear flat wall 211. Additionally, this rear wall is preferably provided with a hub-like rearward extension 212 at its center to accommodate the hub of the large gear wheel 66. This sheet metal casing is held against the rear wall 27 of the cylindrical housing 25 by wing nuts 213 secured to the rear ends of the tie rods 47 and to provide a watertight seal a gasket 214 is preferably interposed between the front edge of the peripheral wall 210 and the bottom part of the rear wall 27 of the cylindrical housing 25.

The can washer and sterilizer embodying my invention can be supported in proper relation to the canway 20 in any suitable manner and for this purpose the lower cylindrical part 25 of the housing is shown as provided in its peripheral wall 26 with horizontally outwardly projecting brackets 215, a pair of these brackets being provided at each side of the can washer and sterilizer, as best shown in Fig. 2. These brackets 215 are provided with half round sockets 216 which are adapted to receive supporting rods 217, as indicated by dotted lines in Figs. 2 and 4. Each of these brackets 215 is also shown as formed to provide a pair of vertically extending ears 218 which are apertured to receive the legs of a U-bolt 219, these U-bolts embracing the supporting rods 217 and holding them firmly in the sockets 216. It will be understood that the supporting rods 217 can be supported in any suitable manner, as by suspending them from the ceiling of the room in which the canning operations are carried on.

Operation

When no cans are being conveyed down the canway 20, the feed and discharge switches 180 and 181 are in the positions shown in Fig. 5 in which the motor 56 and the solenoid 141 are deenergized so that the drive wheel 70 is not rotating and the supply of hot water and steam to the can washer and sterilizer is cut off.

When a line of cans 21 is admitted to the upstream end of the canway 20, the advance end of the line of cans enters the inlet neck 29 and is directed by the shelf 35 against the partition 32, as shown in Fig. 10. This swings the switch arm 187 from its normal pendant position to the full line position shown in Fig. 10, this rocking the rock shaft 186 to which this arm is fixed and swinging the mercury tube type feed switch 181 from the position shown in Fig. 5 to its closed position in which its globule of mercury establishes contact between its lines 175 and 177.

When this occurs a circuit is established through the side 178 of the main power line, solenoid 141, line 175 and through closed mercury tube type switches 181, 180 to the other side 179 of the main power line. The energization of the solenoid 141 moves the valve rod 144, connected to its core, to the left as viewed in Fig. 9 and brings the reduced parts 165 and 166 of this valve into register with the bores in the valve

body. Hot water is thereby permitted to flow from the hot water supply pipe 160, through the bore 159, around the reduced part 166 of the valve stem, through the bore 150, and pipe 122 into the right hand side of the manifold 120 as viewed in Fig. 4, this manifold being blocked at 125. This hot water sprays out through the corresponding nozzles 130 provided in the front wall of the manifold 120, as shown in Figs. 5, 6 and 8, these hot water nozzles being arranged in semi-circular arrangement in the casing 25 to spray hot water into the passing line of cans. This movement of the valve stem 144 to the left, upon energization of the solenoid 141, also permits steam to flow from the steam supply pipe 158, as viewed in Fig. 9, through the bore 157, around the reduced part 165 of the valve stem, through the bore 149 and pipe 124 into the left hand side of the manifold 120, as viewed in Fig. 4. This steam sprays out through the corresponding nozzles 130 provided in the front wall of the manifold 120, as shown in Figs. 5, 6 and 8, these steam nozzles being arranged in semi-circular arrangement in the casing 25 to spray steam into the passing line of cans.

This closing of the mercury tube type feed switch 181 also establishes a circuit through the side 178 of the main power line, line 176, electric motor 56, line 175, and mercury tube type switches 181 and 180 to the other side 179 of the main power line. The energization of the motor 56 drives its pulley 58 (Fig. 3), belt 59 and pulley 60 on the shaft 61. As shown in Fig. 6, the rotation of the shaft 61 drives the pinion 65, gear 66, shaft 67 and rubber tired drive wheel 70, this drive wheel 70 being driven in a counter-clockwise direction, as viewed in Fig. 10.

The leading can of the line of cans 21 drops from the lower end of the switch arm 187 into engagement with the rubber face 72 of this drive wheel and also into engagement with the inner face of the annular series of shoes 75. The rubber face of the drive wheel 70 and the opposing faces of the annular series of shoes 75 are arranged to engage the peripheries of the line of cans and the cans are initially arranged so that their open ends face the water nozzles 130 whereby the interior of the cans are violently sprayed with hot water. Since the axis of the casing 25 and the coaxial shaft 67 and its drive wheel 70 are inclined relative to the horizontal, as illustrated in Fig. 6, this wash water immediately flows out of the cans being sprayed and into the bottom of the casing 25 from which it drains out through the drain 42.

The line of cans interposed between the rubber faced drive wheel 70 and the annular series of shoes 75 are positively propelled in a counter-clockwise direction, being first sprayed with hot water and then with steam from the nozzles 130. This line of cans is not, however, propelled at the same speed as the peripheral speed of the drive wheel 70 as each can is rotated in the manner of a gear, so as to expose all internal parts to the sprays. In the event any of the cans are initially out of round they are trued up upon being pressed and rolled between the drive wheel 70 and the annular series of shoes 75.

In the event that a slightly larger can 21 is encountered, each shoe 75 is mounted to yield slightly. In this event the bell crank lever 86 carrying each shoe 75, as best shown in Fig. 6, can swing clockwise to the extent permitted by the oversize groove 100 in the adjusting collar 101. The return spring 95 for each bell crank

lever 86 serves to yieldingly hold the corresponding shoe 75 against each passing can regardless of inequalities in their size.

The can washer and sterilizer can be set to handle cans of different sizes. For this purpose the axial position of the collar 101 can be adjusted to normally hold the annular series of shoes 75 to the approximate diameter of cans of any size. To so adjust the axial position of the collar 101, the operator turns the nuts 116, Fig. 7, to move the forked lever 111 to the desired can size on the scale plate 112. The lower forked end 109 of the lever, arranged in opposite sides of the oversize groove 100 of the collar 101 serves to adjust this collar to a corresponding axial position.

The line of cans 21 is pushed by the rubber surfaced drive wheel 70 and the last shoe 75, upwardly and out through the outlet neck 31 of the can washer. From this outlet neck the cans roll by gravity down the downstream side of the canway 20 to the next stage of processing.

When the trailing end of the line of cans enters the can washer and sterilizer, the switch arm 181, Fig. 10, is released by the trailing can to fall to its pendant position in which the feed mercury tube type switch 181 is restored to its original open position, as shown in Fig. 5. The motor 56 is thereby deenergized to stop the drive wheel 70 and the solenoid 141 is likewise deenergized to permit the return spring 170, Fig. 9, to return the valve stem 144 axially to its closed position, as viewed in Fig. 9, thereby cutting off the further supply of hot water and steam. The can washer and sterilizer is thereby rendered completely inoperative.

In the event that the movement of the line of cans in the downstream part of the canway 20 is held up, the positive feeding of the cans into the outlet neck 31 by the rubber surfaced drive wheel 70 and the annular series of shoes 75 causes the cans to pile up in the outlet neck 31. By the provision of the step 40 in the outlet neck 31, the can on top of this step is carried to ride up on the preceding can to the dotted line position shown in Fig. 10. This can engages and elevates the shoe 201 which swings the lever 196 and shaft 191 to tip the discharge mercury tube type switch 180 to its open position. Opening this mercury tube type switch 180 breaks the circuit through the motor 56 and 180 breaks the circuit through the motor 56 and solenoid 141 and hence renders the entire can washer inoperative in the same manner as when the feed mercury tube type switch 181 is opened. As soon as the congestion or obstruction in the downstream line of cans from the can washer is relieved, the elevated can in the outlet neck 31 drops back, releasing the shoe 201 to its normal pendant position illustrated by full lines in Fig. 10, this restoring the discharge mercury tube type switch 180 to its closed position and hence reestablishing the circuit through the motor 56 and solenoid 141 to resume the positive feeding of the line of cans through the can washer and their spraying with hot water and steam.

From the foregoing it will be seen that the present invention provides a fully adjustable can washer and sterilizer which can readily be inserted in any canway without disturbing or requiring alteration in the can handling system; which positively conveys the cans past the sprays of hot water and steam; which automatically delivers the cans in a drained, sterilized condition; which automatically starts and stops when

the leading and trailing end of a line of cans enters or leaves the washer; which automatically stops when the cans delivered by the can washer and sterilizer are held up and automatically starts as soon as the obstruction is relieved; which is simple in construction and reliable in operation; and which also serves to true up any cans which happen to be out of round.

I claim as my invention:

1. Apparatus of the character described, comprising a housing, means forming an inlet for a line of cylindrical containers at one side of said housing, means forming an outlet for said line of containers at the opposite side of said housing, a rotary drive wheel journaled centrally in said housing, said drive wheel having a smooth peripheral face adapted to engage the peripheries of said line of containers, an annular series of radially yieldable shoes surrounding said drive wheel and adapted to engage the peripheries of said line of containers on the opposite sides from said drive wheel, said drive wheel driving said line of containers through a circular looped path through the space between said drive wheel and said series of shoes and discharging said line of containers through said outlet, and means for spraying said containers with a cleaning fluid while traversing said circular looped path.

2. Apparatus of the character described, comprising a housing, means forming an inlet for a line of cylindrical containers at one side of said housing, means forming an outlet for said line of containers at the opposite side of said housing, a rotary drive wheel journaled centrally in said housing, said drive wheel having a smooth peripheral face adapted to engage the peripheries of said line of containers, an annular series of shoes surrounding said drive wheel and adapted to engage the peripheries of said line of containers on the opposite sides from said drive wheel, said inlet being formed to direct said line of containers into the annular space between said drive wheel and said series of shoes and said outlet being formed to receive the containers after being conveyed through said annular space by said drive wheel, a plurality of bell crank levers pivoted at their centers to said housing and each having one horizontal arm arranged between a corresponding shoe and the wall of said housing and each having a second arm projecting inwardly toward the axis of said drive wheel, means pivotally connecting each of said horizontal arms with the corresponding shoe, spring means interposed between said bell crank lever and said housing for yieldingly urging said shoes toward said drive wheel and means for spraying said containers with a cleaning fluid while traversing said annular space.

3. Apparatus of the character described, comprising a housing, means forming an inlet for a line of cylindrical containers at one side of said housing, means forming an outlet for said line of containers at the opposite side of said housing, a rotary drive wheel journaled centrally in said housing, said drive wheel having a smooth peripheral face adapted to engage the peripheries of said line of containers, an annular series of shoes surrounding said drive wheel and adapted to engage the peripheries of said line of containers on the opposite sides from said drive wheel, said inlet being formed to direct said line of containers into the annular space between said drive wheel and said series of shoes and said outlet being formed to receive the containers after being conveyed through said annular space by said

drive wheel, a plurality of bell crank levers pivoted at their centers to said housing and each having one horizontal arm arranged between a corresponding shoe and the wall of said housing and each having a second arm projecting inwardly toward the axis of said drive wheel, means pivotally connecting each of said horizontal arms with the corresponding shoe, spring means interposed between said bell crank lever and said housing for yielding urging said shoes toward said drive wheel, means for limiting the movement of said bell crank levers under the influence of said spring and means for spraying said containers with a cleaning fluid while traversing said annular space.

4. Apparatus of the character described, comprising a housing, means forming an inlet for a line of cylindrical containers at one side of said housing, means forming an outlet for said line of containers at the opposite side of said housing, a rotary drive wheel journaled centrally in said housing, said drive wheel having a smooth peripheral face adapted to engage the peripheries of said line of containers, an annular series of shoes surrounding said drive wheel and adapted to engage the peripheries of said line of containers on the opposite sides from said drive wheel, said inlet being formed to direct said line of containers into the annular space between said drive wheel and said series of shoes and said outlet being formed to receive the containers after being conveyed through said annular space by said drive wheel, a plurality of bell crank levers pivoted at their centers to said housing and each having one horizontal arm arranged between a corresponding shoe and the wall of said housing and each having a second arm projecting inwardly toward the axis of said drive wheel, means pivotally connecting each of said horizontal arms with the corresponding shoe, spring means interposed between said bell crank lever and said housing for yielding urging said shoes toward said drive wheel, adjustable means for limiting the movement of said second arms of said bell crank levers under the influence of said spring and means for spraying said containers with a cleaning fluid while traversing said annular space.

5. Apparatus of the character described comprising a housing, means forming an inlet for a line of cylindrical containers at one side of said housing, means forming an outlet for said line of containers at the opposite side of said housing, one wall of said housing being formed to provide a bearing projecting outwardly therefrom, a drive shaft journaled in said bearing, a rotary drive wheel fixed to said drive shaft within said housing, said drive wheel having a smooth peripheral face adapted to engage the peripheries of said line of containers, an annular series of shoes surrounding said drive wheel and adapted to engage the peripheries of said line of containers on the opposite sides from said drive wheel, said inlet being formed to direct said line of containers into the annular space between said drive wheel and said series of shoes and said outlet being formed to receive the containers after being conveyed through said annular space by said drive wheel, an annular series of bell crank levers pivotally secured at their centers to that wall of said housing formed to provide said bearing, each of said bell crank levers being formed to provide a horizontal arm projecting toward a corresponding shoe and a second arm projecting toward said

5 shaft, means for pivotally securing each of said horizontal arms to a corresponding shoe, spring means connected to each bell crank lever for urging its shoe toward said drive wheel, a sleeve mounted on said bearing and having a peripheral groove receiving the corresponding ends of said bell crank levers and limiting their movement under the influence of said springs and means for spraying said containers with a cleaning fluid while traversing said annular space.

6. Apparatus of the character described, comprising a housing, means forming an inlet for a line of cylindrical containers at one side of said housing, means forming an outlet for said line of containers at the opposite side of said housing, one wall of said housing being formed to provide a bearing projecting outwardly therefrom, a drive shaft journaled in said bearing, a rotary drive wheel fixed to said drive shaft within said housing, said drive wheel having a smooth peripheral face adapted to engage the peripheries of said line of containers, an annular series of shoes surrounding said drive wheel and adapted to engage the peripheries of said line of containers on the opposite sides from said drive wheel, said inlet being formed to direct said line of containers into the annular space between said drive wheel and said series of shoes and said outlet being formed to receive the containers after being conveyed through said annular space by said drive wheel, an annular series of bell crank levers pivotally secured at their centers to that wall of said housing formed to provide said bearing, each of said bell crank levers being formed to provide a horizontal arm projecting toward a corresponding shoe and a second arm projecting toward said shaft, means for pivotally securing each of said horizontal arms to a corresponding shoe, spring means connected to each bell crank lever for urging its shoe toward said drive wheel, a sleeve mounted on said bearing and having a peripheral groove receiving the corresponding ends of said bell crank levers and limiting their movement under the influence of said springs, means for 10 15 20 25 30 35 40 45 50 55 60 65 70 75 75 adjustingly moving said sleeve axially of said bearing to limit the normal spacing of said series of shoes from said drive wheel to accommodate said annular space to a particular size of cans being handled and means for spraying said containers with a cleaning fluid while traversing said annular space.

7. Apparatus of the character described, comprising a housing, means forming an inlet for a line of cylindrical containers at one side of said housing, means forming an outlet for said line of containers at the opposite side of said housing, a rotary drive wheel journaled centrally in said housing, said drive wheel having a smooth peripheral face adapted to engage the peripheries of said line of containers, an annular series of radially yieldable shoes surrounding said drive wheel and adapted to engage the peripheries of said line of containers on the opposite sides from said drive wheel, said inlet being formed to direct said line of containers into the annular space between said drive wheel and said series of shoes and said outlet being formed to receive the containers after being conveyed through said annular space by said drive wheel, means for spraying said containers with a cleaning fluid while traversing said annular space and means for rotating said rotary means comprising a countershaft journaled in said housing generally parallel with the axis of said drive wheel, drive means between said countershaft and said rotary

means and an electric motor mounted on said housing and driving said countershaft.

8. Apparatus of the character described, comprising a housing, means forming an inlet for a line of cylindrical containers at one side of said housing, means forming an outlet for said line of containers at the opposite side of said housing, a rotary drive wheel journaled centrally in said housing, said drive wheel having a smooth peripheral face adapted to engage the peripheries of said line of containers, an annular series of radially yieldable shoes surrounding said drive wheel and adapted to engage the peripheries of said line of containers on the opposite sides from said drive wheel, said inlet being formed to direct said line of containers into the annular space between said drive wheel and said series of shoes and said outlet being formed to receive the containers after being conveyed through said annular space by said drive wheel, means for spraying said containers with a cleaning fluid while traversing said annular space and means for rotating said rotary means comprising a countershaft journaled in said housing generally parallel with the axis of said drive wheel, drive means between said countershaft and said rotary means and an electric motor mounted on said housing and driving said countershaft, the axes of said drive wheel, said countershaft and said electric motor being substantially in the same plane.

9. Apparatus of the character described, comprising a housing, means in the upper part of said housing forming an inlet for a line of cylindrical containers, means in the upper part of said housing forming an outlet for said line of containers, a rotary drive wheel journaled centrally in said housing to rotate about an axis inclined at a slight angle to the horizontal, said drive wheel having a smooth peripheral face adapted to engage the peripheries of said line of containers, an annular series of radially yieldable shoes surrounding said drive wheel and adapted to engage the peripheries of said line of containers on the opposite sides from said drive wheel, said inlet being formed to direct said line of containers into the annular space between said drive wheel and said series of shoes and said outlet being formed to receive the containers after being conveyed through said annular space by said drive wheel, said containers being conveyed through said annular space with their axes substantially parallel with the axis of said drive wheel and with their open ends at a lower elevation than their closed ends, means for spraying a cleaning fluid into the open ends of said containers while traversing said annular space and a drain at the lower end of said housing for draining the fluid draining out of said containers.

10. Apparatus of the character described, comprising a housing, means forming an inlet for a line of containers at one side of said housing, means forming an outlet for said line of containers at the opposite side of said housing, said inlet and outlet being substantially in axial alignment with each other, a rotary drive wheel journaled centrally in said housing, said drive wheel having a smooth peripheral face adapted to engage the peripheries of said line of containers, an annular series of radially yieldable shoes surrounding said drive wheel and adapted to engage the peripheries of said line of containers on the opposite sides from said drive wheel, an internal partition formed in said housing between said inlet and said outlet, said partition being formed to direct the containers from said inlet into the annular space between said drive wheel and said

series of shoes and said partition being formed to direct the containers after being conveyed through said annular space by said drive wheel into said outlet and means for spraying said containers with a cleaning fluid while traversing said annular space.

11. Apparatus of the character described, comprising a stationary housing, means forming an inlet for a line of containers at one side of said housing, means forming an outlet for said line of containers at the opposite side of said housing, rotary means within said housing for conducting said line of containers through a circular looped path through said housing and means for spraying said containers with a cleaning fluid while traversing said circular looped path comprising a loop-shaped manifold secured to said housing at one side of the line of containers traversing said circular looped path, a plurality of nozzles provided in said manifold and directing cleaning fluid therefrom into the passing line of containers and means responsive to the presence of containers for supplying said cleaning fluid to said manifold.

12. Apparatus of the character described, comprising a stationary housing, means forming an inlet for a line of containers at one side of said housing, means forming an outlet for said line of containers at the opposite side of said housing, rotary means within said housing for conducting said line of containers through a circular looped path through said housing and means for spraying said containers with a cleaning fluid while traversing said circular looped path, comprising a loop-shaped manifold formed integrally with one of the side walls of said housing and arranged alongside the line of containers traversing said circular looped path, a plurality of nozzles removably secured to said manifold and arranged to direct sprays of cleaning fluid from said manifold into the passing line of containers, and means responsive to the presence of containers for supplying said cleaning fluid to said manifold.

13. Apparatus of the character described, comprising a stationary housing, means forming an inlet for a line of containers at one side of said housing, means forming an outlet for said line of containers at the opposite side of said housing, rotary means within said housing for conducting said line of containers through a circular looped path through said housing, an electric motor driving said rotary means, an arm arranged in the path of the line of containers entering said housing, a normally opened switch actuated by said arm, said arm being moved by the leading end of the line of containers to close said switch, said switch being in circuit with said motor thereby to energize said motor in response to the movement of the line of containers into said housing and means for spraying said containers with a cleaning fluid while traversing said circular looped path.

14. Apparatus of the character described, comprising a stationary housing, means forming an inlet for a line of containers at one side of said housing, means forming an outlet for said line of containers at the opposite side of said housing, rotary means within said housing for conducting said line of containers through a circular looped path through said housing, an electric motor driving said rotary means, means for spraying said containers with a cleaning fluid while traversing said circular looped path, a normally closed electrically actuated valve controlling the admission of cleaning fluid to said spraying

means, an arm arranged in the path of the line of containers entering said housing, and a normally opened switch actuated by said arm, said arm being moved by the leading end of the line of containers to close said switch, said switch being in circuit with said motor and said electrically actuated valve thereby to energize said motor and open said valve in response to the movement of the line of containers into said housing.

15. Apparatus of the character described, comprising a stationary housing, means forming an inlet for a line of containers at one side of said housing, means forming an outlet for said line of containers at the opposite side of said housing, rotary means within said housing for conducting said line of containers through a circular looped path through said housing, an electric motor driving said rotary means, a movable arm arranged adjacent the line of containers leaving said housing and arranged to be moved in response to the congestion of said line of leaving containers caused by an obstruction to their movement beyond said housing, a normally closed switch actuated by said arm, said arm being moved in response to said congestion of containers to open said switch and deenergize said motor when said congestion occurs and means for spraying said containers with a cleaning fluid while traversing said circular looped path.

16. Apparatus of the character described, comprising a stationary housing, means forming an inlet for a line of containers at one side of said housing, means forming an outlet for said line of containers at the opposite side of said housing, rotary means within said housing for conducting said line of containers through a circular looped path through said housing, an electric motor driving said rotary means, means for spraying said containers with a cleaning fluid while traversing said circular looped path, a normally closed electrically actuated valve controlling the admission of cleaning fluid to said spraying means, a movable arm arranged adjacent the line of containers leaving said housing and arranged to be moved in response to the congestion of said line of leaving containers caused by an obstruction to their movement beyond said housing, a normally closed switch actuated by said arm, said arm being moved in response to said congestion of containers to open said switch, said switch being in circuit with said motor and said electrically actuated valve thereby to deenergize said motor and close said valve in response to the movement of said switch arm when said congestion occurs.

17. Apparatus of the character described, comprising a stationary housing, means forming an inlet for a line of containers at one side of said housing, means forming an outlet for said line

of containers at the opposite side of said housing, rotary means within said housing for conducting said line of containers through a circular looped path through said housing, an electric motor driving said rotary means, an arm arranged in the path of the line of containers entering said housing, a normally opened switch actuated by said arm, said arm being moved by the leading end of the line of containers to close said switch, a movable arm arranged adjacent the line of containers leaving said housing and arranged to be moved in response to the congestion of said line of leaving containers caused by an obstruction to their movement beyond said housing, a normally closed switch actuated by said arm, said arm being moved in response to said congestion of containers to open said switch, means connecting said switches in series with said motor and means for spraying said containers with a cleaning fluid while traversing said circular looped path.

18. Apparatus of the character described, comprising a stationary cylindrical housing having a substantially horizontal axis, means at the top of said housing forming an inlet for a line of containers, means at the top of said housing forming an outlet for said line of containers, said inlet and outlet opening in opposite directions and being in line with each other along an axis which is substantially tangential to said housing, a rotor arranged substantially concentrically within said housing to rotate about said axis of said housing, means carried by said rotor and said housing to move said containers through a circular looped path around the peripheral wall of said housing through motion derived from said rotor, means for spraying said containers with a cleaning fluid while traversing said circular looped path and means for rotating said rotor.

19. Apparatus of the character described, comprising a stationary cylindrical housing having its axis slightly inclined from the horizontal, means at the top of said housing forming an inlet for a line of containers, means at the top of said housing forming an outlet for said line of containers, said inlet and outlet opening in opposite directions and being in line with each other along an axis which is substantially tangential to said housing, a rotor arranged substantially concentrically within said housing to rotate about said axis of said housing, means carried by said rotor and said housing to move said containers through a circular looped path around the peripheral wall of said housing through motion derived from said rotor, means for spraying said containers with a cleaning fluid while traversing said circular looped path and means for rotating said rotor.

WILLIAM DE BACK.
